(No Model.)

E. ALLEN.

MACHINE FOR CUTTING SPOOL BLANKS.

No. 247,593.

Patented Sept. 27, 1881.

UNITED STATES PATENT OFFICE.

EDWIN ALLEN, OF NORWICH, CONNECTICUT, ASSIGNOR TO THE ALLEN SPOOL AND PRINTING COMPANY, OF SAME PLACE.

MACHINE FOR CUTTING SPOOL-BLANKS.

SPECIFICATION forming part of Letters Patent No. 247,593, dated September 27, 1881.

Application filed June 8, 1881. (No model.)

To all whom it may concern:

Be it known that I, EDWIN ALLEN, of Norwich, in the county of New London and State of Connecticut, have invented certain new and 5 useful Improvements in Machines for Cutting Spool-Blanks, &c., of which the following is a specification.

The object of the invention is to provide a machine whereby a number of spool-blanks or 10 analogous articles may be cut off from a stick or rod at one operation by means of a number or gang of saws, and in which provision is made for holding the blanks or pieces as they are cut off by the saws.

15 The invention consists, essentially, in the combination, in a machine for cutting spool-blanks or analogous articles, of a saw-mandrel and saws movable laterally toward and from the work, a holdfast consisting of a pair of gripping-jaws, 20 between which the stick or rod of wood is fed, and one of which is slotted to permit of the passage of the saws through it, and means for causing said jaws to grip the stick or rod between the several saws during the cutting operation and to release the blanks at the completion of the cutting operation. One of said jaws is preferably fixed, while the other is pivoted, and said pivoted jaw is acted upon by a 25 spring to move it to release the spools or other articles, and by suitable operating mechanism, such as a cam, to move it to cause it, in connection with the fixed jaw, to grip the spools or other articles.

In the accompanying drawings, Figure 1 represents a plan view, partly in section, of a machine embodying my invention, and comprising a hollow rotary spindle, through which the sticks or rods are fed, and which carries knives or cutters for turning the same. Fig. 2 represents a vertical transverse section upon the line *x x*, Fig. 1, Fig. 3 representing a detail sectional view illustrating the mode of operation of the gripping-jaws; and Figs. 4 and 5 are detail views, to be hereinafter described.

45 Similar letters of reference designate corresponding parts in all the figures.

A designates the frame-work of the machine, and B designates a driving-shaft, mounted in bearings near the bottom of the machine and extending longitudinally the whole length thereof.

The driving-shaft B may be rotated by a driving-belt passing around the pulley B'.

C designates a frame, which is supported at the lower end upon the shaft B, and is adapted to swing freely back and forth upon such shaft 55 as a fulcrum, although the shaft is free to rotate within it.

In the upper end of the frame C are bearings for a saw-mandrel, *a*, upon which are secured several saws, *b*, side by side, (here shown as 60 three in number,) and secured at a distance apart equal to the length of the spool or other blanks to be cut off. When the frame C is swung slightly upon its fulcrum the saw-mandrel *a* is moved transversely with its saws. The 65 saw-mandrel *a* may be rotated by means of a belt, *c*, passing over a pulley, *d*, upon the shaft B and another pulley, *d'*, on the saw-mandrel.

The frame C is swung or moved in one direction by a spring, *e*, (best seen in Fig. 2,) which is 70 connected with said frame and with the framework of the machine, and said frame C is swung or moved in the opposite direction against the force of said spring by a cam, *f*, fixed to the shaft *g*, as shown clearly in Fig. 1.

75 At the upper part of the machine is journaled a counter-shaft, D, which is rotated by means of a belt, D', passing round a pulley, D², on the shaft B, and a pulley, D³, on the counter-shaft D, and from said shaft rotary motion is transmitted through a pinion, *g'*, and a wheel, *g²*, upon the shaft *g*.

E designates a hollow spindle mounted in bearings in a cross-piece or stock, A', and carrying at its forward end knives or cutters *h*, 85 which are adapted to act upon a stick or rod of wood thrust through the spindle, and said spindle may be rapidly rotated by means of a belt passing from a pulley (not here shown) on the shaft B over a pulley, E', on the spindle E.

F designates a carriage movable along the top of the frame-work of the machine, and carrying a socket, F', into which the end of a stick of wood may be inserted, as seen clearly 95 in Fig. 1, and which will hold said stick against turning while passing through the spindle E to subject it to the cutters *h*. The stick might, however, be fed forward by hand.

The carriage F carries a pawl, *i*, which en-

gages with ratchet-teeth or notches i' in a bar or rod, G , which is connected at j to one end of a lever, H , the other end of which is fulcrumed at j' . Upon the shaft g is fixed a cam, l , upon which is a projection, l' , (see Figs. 1 and 4,) which as said cam turns bears upon a projection or lug, m , on the lever H and moves the latter, thereby drawing the rod G forward, and with it the carriage F , by means 10 of the connection of the pawl i with the teeth or notches i' in said rod. The rod G is moved backward to take a new hold on the carriage F by means of a spring, G' . (Shown in Fig. 1.)

Referring now to the parts which form the 15 principal feature of my invention, J designates a yoke or saddle extending across the machine above the saws b , and carrying a holdfast, which consists of jaws n n' , between which the turned stick passes as it issues from the low spindle E . The jaw n is represented as 20 rigid, it consisting in this instance of a projection on the yoke J ; and the jaw n' is pivoted at n^2 , and is adapted to turn on its pivot to open or close it relatively to the fixed jaw n .

When not otherwise actuated, the jaw n' is 25 moved away from the jaw n by a spring, o , to release the stick and permit it to be shoved freely forward between the jaws, and said jaw n' is moved in the other direction and against 30 the force of the spring o , to cause it, in connection with the jaw n , to gripe the wood by a cam, p , upon the end of a short pin or shaft which has a bearing in the yoke J . Upon the opposite end of said short pin or shaft is fixed 35 a disk, r , to which are connected a spring, r' , for turning or oscillating the disk in one direction, and a rod, s , for turning or oscillating the disk in the other direction, as best seen in Figs. 3 and 5. The lower end of the rod s 40 is bifurcated, as seen in Fig. 3, so as to pass over and be guided by the shaft g , and upon said shaft is fixed a cam, s' , which acts upon a pin, s^2 , projecting from said rod to raise the latter and turn the disk r against the force of 45 the spring r' .

When the cam s' and the other parts are in the position shown in Fig. 3, and while the saws b are cutting the stick, the jaw n' is caused to gripe the stick by means of the spring r' , 50 which turns the disk r , and with it the cam p , and the stick is so gripped until the portion held has been cut into spools, whereupon the disk r and cam p are oscillated or turned in the opposite direction by the rod s , and the 55 spring o acts upon the jaw n' to move it away from the jaw n , and thus permits the several spool or other blanks to drop into a box or other receptacle.

By the two jaws n n' the spool or other 60 blanks are held firmly as they are cut off by the several saws, and are prevented from being

thrown in all directions when they are cut off, as they would be if not held.

As here represented, the fixed jaw n is notched or has saw cuts or slits in it at intervals to 65 permit the saws b to pass through it, thus forming fingers between the several saws and on the outer side of the two outside saws, and the movable jaw n' is notched slightly in its face to permit of the saws entering it slightly to 70 make sure of their cutting entirely through the stick or rod of wood.

It is obvious that instead of the jaw n' being 75 movable to release the work the jaw n , or both jaws, might be movable, and in place of either jaw a series of fingers might be employed; but in the latter case the fingers would all move simultaneously to gripe or release the blanks, and might be very properly regarded as one jaw.

By my invention I provide a machine which is automatic in its action, if the sticks of wood are supplied and placed in the machine as fast as used up, and which will turn and cut off spool-blanks with great rapidity, and consequently at small cost.

I am aware that it is old to construct a spool-machine with a saw movable toward the stick or rod of wood to sever the same into spool-blanks, and a rotary receiver consisting of a 90 wheel or disk having peripheral recesses, through which the stick or rod of wood is thrust, and which serves to support the blank after being cut. Such rotary receiver does not, however, gripe a stick or rod of wood as 95 do my jaws, and the blanks are not delivered from the receiver until the latter has made a partial rotation.

What I claim as my invention, and desire 100 to secure by Letters Patent, is—

1. In a machine for cutting spool blanks or analogous articles, the combination of a saw-mandrel and saws, movable laterally toward and from the work, a holdfast consisting of a pair of gripping-jaws, between which the stick or rod of wood is fed, and one of which is slotted to permit of the passage of the saws through it, and means for causing the jaws to gripe the stick or rod between the several saws during the cutting operation and to release 110 the blanks at the completion of the cutting operation, substantially as specified.

2. The combination of the swinging frame C , the saw-mandrel a , and saws b , the fixed and movable jaws n n' , the cam p , acting upon 115 said movable jaw, the spring o , acting upon said jaw, and the spring r' , rod s , and cam s' , for actuating said cam p , substantially as specified.

Witnesses: EDWIN ALLEN.
